UNITED STATES PATENT OFFICE.

CHARLES L. HENSLEY, OF WHITE BLUFFS, WASHINGTON.

EXHAUST-MUFFLER.

943,544.

Specification of Letters Patent. Patented Dec. 14, 1909.

Application filed April 21, 1909. Serial No. 491,406.

To all whom it may concern:

Be it known that I, CHARLES L. HENSLEY, a citizen of the United States, residing at White Bluffs, in the county of Benton and State of Washington, have invented new and useful Improvements in Exhaust-Mufflers, of which the following is a specification.

This invention relates to mufflers for deadening the sound of the exhaust from engines; the muffler hereinafter described being especially designed for use on gasoline engines and being adapted to automatically provide an outlet for the exhaust in proportion to the speed of the engine and the amount of exhaust gases escaping therefrom.

With the above general object in view the invention consists in the novel construction, combination and arrangement of parts as herein fully described, illustrated and claimed.

In the accompanying drawings:—Figure 1 is a diametrical section through a muffler embodying the present invention. Fig. 2 is a cross section through the same on the line 2—2 of Fig. 1 looking in the direction of the arrow. Fig. 3 is a detail diametrical section showing the exhaust ports open.

In the preferred embodiment of this invention, I employ a hollow cylindrical muffler body 1 of suitable dimensions according to the size of the engine, said muffler body being closed at one end by a head 2 while the opposite end of the muffler body may be left open as indicated at 3. The head 2 is provided with a threaded opening 4 to receive the threaded end of the exhaust pipe 5 leading from the engine to the muffler.

Adjacent to the head 2, the body of the muffler is formed with an annular series of exhaust ports 6 which are adapted to be opened and closed by the cylindrical port closure face 7 of a valve 8 which is mounted for reciprocatory movement in the muffler body. The valve 8 is provided with an inwardly offset-cylindrical portion 9 at the extreme edge of which there is provided a stop flange 10 extending outwardly therefrom. In conjunction with the valve 8 I employ a reciprocating piston 11 of hollow construction embodying a cylindrical outer wall 12 which works in contact with the inner surface of the muffler body 1 and outside of and around the cylindrical wall 9 of the valve. At its extreme edge, the wall 12 of the piston is provided with an annular stop

shoulder 13 extending inwardly therefrom in close proximity to the outer surface of the cylindrical wall 9 of the valve.

By the arrangement just described and clearly illustrated in Figs. 1 and 3 it will be seen that the piston 11 and the valve 8 have a limited movement or play relatively to each other; in other words, under the impact or pressure of the exhaust, the piston 11 is adapted to move a predetermined distance equal to the space between the stop flange 10 and the shoulder 13 before the piston will operate to move the valve 8 for the purpose of uncovering the exhaust ports 6.

The muffler body at its outer end is provided with a rim 13 extending inwardly and terminating in an inturned flange 14 thereby leaving an annular groove 15 which forms a seat for the outer end of a coil spring 16, the opposite end of which bears against the piston 11. Preferably the piston 11 is rabbed at 17 to form a seat for the inner end of the spring 16 as clearly shown in Fig. 1; in this way the spring is held centrally within the muffler body and prevented from working in contact with the inner wall of the muffler body. The spring 16 acts to force the piston back to its initial position shown in Fig. 1, causing the stop shoulder 13 to operate against an annular shoulder 18 on the valve, thereby forcing the valve back to its closed position as shown in Fig. 1. In the outward movement of the piston 11, the valve 8 is moved by the piston until the ports 6 are uncovered as shown in Fig. 3. The spring 16 may be of any suitable size and tension proportionate to the size of the engine and the pressure of the exhaust delivered therefrom. The construction above described provides for a light and efficient muffler which will practically muffle the noise of the exhaust from the engine and which will automatically accommodate itself to the pressure of the exhaust and liberate the same accordingly.

I claim:—

1. An exhaust muffler comprising a receiving chamber having outlet ports, a valve adapted to open and close said ports, and an exhaust pressure-operated piston adapted to shift said valve.

2. An exhaust muffler comprising a receiving chamber having outlet ports, a valve adapted to open and close said ports, an exhaust pressure-operated piston adapted to shift said valve, and means for returning the

valve to a closed position after the exhaust gas has escaped.

3. An exhaust muffler comprising a receiving chamber having outlet ports, a valve adapted to open and close said ports, and an exhaust pressure-operated piston adapted to shift said valve, the valve and piston being provided with coöperating shoulders.

4. An exhaust muffler comprising a receiving chamber having outlet ports, a valve adapted to open and close said ports, and an exhaust pressure-operated piston adapted to shift said valve, the valve and piston having a limited free relative movement in the direction of pressure of the exhaust.

5. An exhaust muffler comprising a receiving chamber having outlet ports at the

same end as that at which the exhaust enters, a valve adapted to open and close said ports and an exhaust pressure-operated piston adapted to shift said valve.

6. An exhaust muffler comprising a receiving chamber having outlet ports, a hollow exhaust pressure-operated piston, and a valve adapted to open and close said ports and also coöperating with and adapted to be actuated by said piston.

In testimony whereof I affix my signature in presence of two witnesses.

CHARLES L. HENSLEY.
